ABSTRACT: The hanging dismountable partition for industrial buildings comprises a suspension iron part of U-shape whose end is fixed to the roofing of the building and whose flanges have a series of holes for positioning pins from which partially overlapping panels are suspended and on which other similar panels are hooked also overlapping each other and the superimposed panels. The panels of the various rows hanging from those hooked on the suspension iron parts are respectively provided with a rigid stem, of substantially T-shape, offset in relation to one of the lateral faces of the panel to an extend very slightly greater than the thickness of the panel and loosely sliding in a member carried by the panel immediately above it.

SUSPENDED DISMOUNTABLE PARTITIONS FOR INDUSTRIAL BUILDINGS

It is important, in many industrial buildings, particularly in warehouses, to divide up covered surfaces, in which various products or material are stored. For this purpose, removable partitions are generally used, said partitions being often made by means of prefabricated members that can be self-assembled. These partitions enable batches of products or material of different kinds to be isolated, and are also intended to limit the risks of causing fire.

It has, however, been noticed that the partitions used up to now only imperfectly carry out the second function mentioned above. Most frequently buildings do not have a flat roof, but on the contrary, since roofs have one or more slopes, it would be exceptional that removable partitions could be erected up to the roof without leaving any free space. There is thus nearly always, immediately below the roof, areas where air can rapidly circulate, and these areas increase the risks of causing fire by generating hot gases along the roof if a fire should take place in one of the compartments confined by the partitions.

The present invention seeks to obviate the above-mentioned disadvantage by creating a new suspended partition which can be very easily put up and taken down. The suspended partition of the invention prevents any air circulation passage level with the roof, whatever the slope this roof may have, so that a circulation of hot gas in the case of fire is prevented.

According to the invention, the partition includes a substantially U-shaped suspension part whose end is fixed to the roofing of the building and whose flanges have a series of holes receiving pins, panels being pivotally carried by said pins and overlapping one another. The panels include hooks on which other similar panels are hooked, these similar panels also overlapping each other in the first-mentioned panels. The panels are disposed in vertical rows, each panel being provided with a rigid stem of substantially T-shape offset in relation to one of the lateral faces of the panel and loosely sliding in the hook of the panel immediately thereabove whereby the panels may pivot around the respective pins or hooks to be vertically disposed regardless of the slope of the roofing.

Various other characteristics of the invention will be revealed by the detailed description which follows.

An embodiment of the invention is shown, by way of non-restrictive example, in the attached drawing.

FIG. 1 is a partial front elevation, partly in section, of the partition.

FIG. 2 is a front elevation of one of the elements forming the partition.

FIG. 3 is a cross elevation taken along the line III-III of FIG. 2.

FIG. 4 is a cross section on a larger scale, substantially along the line IV-IV of FIG. 1.

FIG. 5 is a partial section, on a larger scale, along the line V-V of FIG. 1.

FIG. 6 is a partial front elevation similar to FIG. 1 and showing another characteristic position of the partition.

FIG. 7 is a partial front elevation of another embodiment.

The partition is intended to be mounted at the top part of a building comprising walls 2 and a roof 3. The partition, intended to form a protecting screen against a possible fire, comprises one or more U-shaped metal parts 6, for example, of bent steel plating, provided on their end with fixing members—not shown—for attaching to the roof 3. These fixing members can be made in numerous different ways for ensuring, either definite fixing, or removable mounting, when it is necessary frequently to change the place of the hanging partitions as a function of the dividing up of the covered surface afforded by the building.

The metal parts 6 comprise two flanges 6a and 6b with equidistant holes for positioning pins 9 for pivotally suspending the panels 10 forming the partition.

Each panel 10 consists, as shown in FIGS. 2 and 3, of a flat disc 20 preferably made of thin iron sheet including a rigid

5 radial stem 21 whose end part comprises two lateral extensions 22. The stem 21, which is substantially of T-shape, is offset laterally in relation to one face of the disc 20 to an extent slightly greater than the thickness of the disc. The disc 20 also comprises, between its center and the part of its periphery from which the stem 21 extends, a member or stirrup piece 23 fixed, in any suitable removable manner, to the opposite face of the disc. The member 23, which is placed crosswise to the radial axis of the stem 21, forms internally a passage 24 whose height is slightly greater than the thickness of the stem 21 and whose width is less than the dimension between the extreme edges of the extensions 22.

10 For making the partition, the stems 21 of a first row of panels 10 are pivotally connected to the iron parts 6 by pins 9 extending through the flanges 6a and 6b and in the holes 25 made in the stems 21 of said panels 10. The distance between the holes provided in the flanges 6a and 6b for inserting the pins 9 is so chosen that two panels 10 that are contiguous partially overlap, confining overlapping areas 13 and extending at least up to the level of one of the iron flanges 6, for example, flange 6a. Then a second row of panels 10 is used whose stems 21 may or may not have the hole 25. Each panel 10 forming the second row is placed on the corresponding panel 10 of the first row, so that the stems 21 are placed according to the same vertical axis while partially overlapping. The holding of the second panel is ensured by member 23 engaging the stem 21 of the second panel, said member 23 being completely fixed on the disc 20 of the first panel. The second panel 10 thus mounted can slide in relation to the first panel to a dimension corresponding to the radial extent of the stem 21 between the corresponding peripheral edge of the disc 20 and the lateral extensions 22. As can be seen in FIG. 4, the mounting of the second panel 10 is made so that the lateral offsetting of the stem 21 is placed in the same direction as that of the stem 21 of the first panel. It follows that between the two assembled panels, there exists a space 26 corresponding to the thickness of the discs 20. An arrangement of this kind is chosen so that it is possible laterally to overlap the various panels forming each row, and make overlapping areas 13 between two contiguous panels.

15 According to the height of the partition to be made, several rows of panels are assembled and in FIG. 1, the partition comprises five horizontal rows of panels mutually overlapped. In this arrangement, it should be noticed that the lateral offsetting of the stems 21 (FIG. 4) means that the member 23 of each panel is placed in the exact extension of the disc 20 of the panel immediately below, without then forming an obstacle preventing the free sliding of the stem 21 of a third panel 10.

20 The final setting up of the partition, for instance, after positioning five rows of discs 20, is done by mounting a lower iron part 6₁ by means of pins 9 passing through the discs 20 of the lower panels 10. To this end, the discs 20 of the panels used for making the last row advantageously have a hole 27 in each one of them at a point diametrically opposed to the stem 21.

25 The partition made as described above is then attached to the roof 3 to extend vertically between the walls 2 which are each provided with a vertical column 28. Each column has at least one hole 29 for engaging a resilient bolt 30 mounted on the end of the lower iron part 6₁. The position of the hole 29 in each column 28 is chosen in relation to the roof 3 so that the engaging of resilient bolts 30 of the iron part 6₁ ensures holding of said iron part in a maximum retracted position of the partition for which the panels 10 have been subjected to a relative sliding corresponding to the radial dimension of the stem 21 and comprised for each panel between the extreme edge and the extensions 22. Each panel 10 is thus substantially held abutting on either side of the associated stem 21 against the member 23 of the panel 10 immediately thereabove. So that the partition has no empty space, especially level with the edges of the extreme vertical rows of panels 10, the iron parts 6 and 6₁ are connected by plates 31 telescopically inserted on the columns 28 for covering the various discs 20 for an extent appreciably equal to half the overlapping areas 13. In this

manner, the partition has no empty space since the various panels 10 are mutually overlapped by their discs 20 for confining the covering areas 13, and are also partially inserted in the iron parts 6 and 6₁ and being also covered by the plates 31 with regard to the discs 20 of the extreme vertical rows of panels 10.

The partition described above is preferably—but not necessarily—mounted as a removable partition placed inside a building for dividing up the covered surface with a view to separating different batches of products or materials. Should fire break out in one of the compartments defined inside the building, the unbolting of the bolts 30 is effected automatically or by hand so as to release the lower iron part 6₁ which is moved vertically by gravity. During the descending movement of the iron part 6₁, the lower panels 10 slide by their stems 21 in the members 23 of the panels immediately above, up to the moment when the lateral extensions 22 bear on said members. It then follows that the row immediately above the discs 20 is also moved in a vertical descending direction for controlling, in a similar manner, the sliding of the panels of the row immediately above. In this manner, an extension of the partition is made so that the iron part 6₁ bears on the top edge of the removable partition dividing the covered surface of the building with a view to totally isolating two contiguous compartments so as to limit the risks of causing a fire.

In the extended position shown in FIG. 6, it should be noticed that the discs 20 of the various panels 10 are always mutually overlapped showing overlapping areas 13. Likewise, the vertical downwards movement of the iron parts 6₁ entails the telescopic sliding of the various plates 31, so that the partition has no intermediate empty space capable of permitting a draught or hot gas to circulate, which could cause a fire.

The possibility of extending the partition is obviously determined by the radial length of the stem 21 of each panel 10 used and by the number of superimposed panels forming vertical rows. Those various data are generally chosen as a function of the space that must be filled in with relation to the fixed or movable partition dividing the covered surface of the building, but it is obvious that in certain cases the ability to extend the partition may be greater than the opening to be closed. In such case, the extension of the partition is limited when the iron part 6₁ abuts against the top edge of the partition or against the ground.

In the example shown in the drawing, the partition comprises vertical rows respectively formed by five superimposed panels 10. FIG. 7 shows the case when the roofing 3' of the building has one or more slopes; the necessary compensation for holding the iron part 6₁ in a horizontal plane is ensured by interposing, at the corresponding level, vertical rows comprising a greater or smaller number, of panels 10.

In FIG. 7, each panel 10 comprises instead of the disc 20, a rectangular plate 20a whose small sides can be rectilinear or curvilinear. The invention is not restricted to the examples shown and described in detail, and various modifications can be made.

I claim:

1. A dismountable partition to be hung from the roofing of industrial buildings characterized in that it comprises a substantially U-shaped suspension part whose end is fixed to the roofing of the building and whose flanges have a series of holes, pins received in said holes, panels pivotally carried by said pins and overlapping one another, said panels including

hooks on which other similar panels are hooked, said similar panels also including hooks and overlapping each other and the first-mentioned panels, said other panels being disposed in vertical rows hanging from those on the suspension part and each being provided with a rigid stem of substantially T-shaped, offset in relation to one of the lateral faces of the associated panel to an extent greater than the thickness of the panel and loosely sliding in the hook carried by the panel immediately above it whereby the panels may pivot around the respective pins or hooks so as to be vertically disposed regardless of the slope of the roofing.

2. A partition according to claim 1, characterized in that the lowermost panels are connected by pins to a substantially horizontal part whose ends are connected to the ends of the suspension part by telescopic vertical plates cooperating with vertical guiding columns.

3. A partition according to claim 2, characterized in that the bottom part is provided with two heat-responsive resilient bolts automatically unclamped in case of fire and intended to be engaged in or released from at least two holes in the guiding columns for insuring the holding of the partition in two particular positions when the panels of each row are, on the one hand, respectively abutting by their corresponding edge against the members of the panels of the row immediately above, corresponding with a maximum retraction position of the partition, and on the other hand, relatively displaced to a maximum extent equal to the travel of the stems inside the superimposed members and corresponding to an extension position of said partition in which the bottom iron part presses on the edge of a partition dividing the covered surface of the building.

4. A partition according to claim 1, characterized in that the stem of each panel comprises two lateral extensions at its free end which form abutments cooperating with the hook carried by the panel immediately above it for limiting the displacement movement of the stem inside said hook.

5. A partition according to claim 1, characterized in that the consecutive panels of the partition are respectively mounted and assembled one on the other so that all the stems are laterally offset in the same direction.

6. A partition according to claim 1, characterized in that the hook of each panel has a thickness substantially equal to that of the panels and defines a passage whose height is slightly greater than the thickness of the stems and whose width is less than that between the extreme edges of the lateral extensions of said stems.

7. Partition according to claim 1, characterized in that the panels are formed by circular plates.

8. Partition according to claim 1, characterized in that the panels are formed by substantially rectangular plates.

9. A dismountable partition to be hung from the roofing of industrial buildings comprising suspension means adapted to be connected to the roofing of a building, a plurality of panels carried by said suspension means, said panels defining a plurality of vertical rows of panels slideably connected with one another between a retracted position and an extended position wherein the panels in each vertical row overlap one another in a vertical direction, said panels including offset portions defining spaces between adjacent panels in each vertical row receiving panels from an adjacent vertical row whereby panels in adjacent vertical rows overlap one another in a horizontal direction.
